UNITED STATES PATENT OFFICE.

WILLIAM F. DIETZSCH, OF CHICAGO, ILLINOIS.

PROCESS FOR RECLAIMING TAR AND LIGHT OIL.

Application filed December 17, 1924. Serial No. 756,381.

My invention relates to a method of and means for reclaiming tar and light oils from the wash tar and wash oils which are produced as a by-product of the manufacture 5 of water gas.

While I have applied my invention in practice to the recovery or reclaiming of tar and oils from the otherwise refuse materials produced in the manufacture of water gas, I do not intend to limit the invention to this particular use, as I believe that the same apparatus and treatment will be applicable to materials of similar character from other sources and I consider the same to come 15 within scope of my invention.

In the manufacture of water gas, the gas, after it is formed in the generator, passes over into the carburetor where petroleum oils are cracked to enrich the product. After passing the carburetor, the gas passes through a superheater and then through a water seal and then through a cooling or spray tower and from there to an equalizer reservoir. It may be treated for the removal of sulphur, and so forth, at intermediate stages, but the above stages are the essential steps in the process as now employed. The gas passing through the water seal is relatively hot. It is cooled by contact with the water, through which it bubbles in the hydraulic main. Here a certain part of the tar and oils are condensed out of the gas stream. The gas then passes on to the cooler and condenser, where it is further cooled and the tar and oils condensed out of the same. The wash oils and tar pass the hydraulic main and the condensate from the cooler or condenser are then run off to a settling well where, according to the prior practice, the light oils are vented off to atmosphere and the tar is supposed to settle or precipitate. The water or water solution of various salts is run back to the hydraulic main.

It has been found that while some of the tar separates out readily, it is extremely difficult to cause the tar to settle or precipitate wherever it has formed an emulsion with the water. As a result, a good deal 50 of the mixture or emulsion must be disposed of under difficulties, as it is not salable and it is only a nuisance.

It appears that the mixture of tar, oils, and water forms an emulsion which will not stratify or separate, and the material 55 becomes impossible to dispose of, as it often

takes a longer time than can be granted in the settling well for sufficient of the oil to evaporate or stratify and the tar to settle out, to make the liquid workable for a water seal.

The stuff will not burn readily because of the large water content. It cannot be sold as tar because of the large water content. It cannot be disposed of for the oil that there is in it because no previously known process of recovery has yielded sufficient oils to make the process of recovery profitable. The liquid emulsion cannot be discharged into the sewer as it clogs up the same. It cannot be discharged into a stream or lake because of the deleterious effect on animal and vegetable life. Besides legislation has stopped this disposal. The tar, if it could be gotten out, could be marketed, so long as it does not contain too great a percent of water.

From my experience, I have found that the stuff is a serious problem. It seems that the light oils which are combined with the tar make a mixture or emulsion in water which emulsion has a specific gravity of about 1.01 to 1.03. The slight difference in specific gravity and the relative viscosity of the mass prevents any separation of the constituents by settling at ordinary temperatures and pressures. The light oils have a specific gravity of about 1.70 to .85, whereas the tar has a specific gravity of approximately 1.07 to 1.12. Thus, in an emulsion of say from 4 to 5% light oil, and tar around 10 to 15%, and water between 70 to 90%, the resultant emulsion is of a specific gravity so near that of water, particularly when the water contains other impurities and salts, that ordinary gravity separation is not feasible or effective.

A great many methods of separation have been tried. None is generally applicable to commercial operation. It costs more to separate the constituents than they are worth. The most common method is to boil the mixture to drive off the water, leaving the tar relatively free of water. This requires a great expenditure of heat to vaporize off the water. The tar may be raised to approximately 400 to 500° F., and even then the water is not all driven off.

Another process that has been tried is that of centrifuging the emulsion. It has been generally unsuccessful, first because of excessive cost of the operation and, next be-

cause everything about the apparatus becomes clogged with heavy tar and carbon.

Another method that has heretofore been tried is working, churning, or mechanically compacting the tar to get it in sufficiently compact form, free of water, and carbon, as to make it salable. This also has been unsuccessful.

Another scheme that has been tried is that 10 of filtering, but the same has not proven to be successful commercially.

Other attempts with which I am not familiar have been tried, but up to the present no process or apparatus has appeared 15 on the market for extracting the tar from the other ingredients, or for extracting any of the other ingredients from the mixture or emulsion.

I have tried the matter of boiling off the 20 water and light oils, but I find that this is only an emergency process to get rid of the stuff. The immense amount of heat required for vaporizing off (latent heat of vaporization), say 70 to 85% of water to 25 get from 10 to 15% tar, makes the fuel cost higher than the value of the recovered material. The settling well is purposely left open to atmosphere, so that some of the light oils may escape and assist in the precipitation of the tar. This removes such light oils as a possible by-product as heretofore practiced.

Finding that I was compelled, by necessity, to dispose of the emulsion, I experimented with the material in a small experimental still with a glass side, to permit of observation of the action involved. Upon heating up the emulsion I found that boiling of the mass kept the whole 40 emulsion in such a state of agitation that the tar would only slowly settle out and it was necessary to drive off the water and light oils by continued boiling. The last 45 part of the water was found to be difficult to extract. In fact, after the temperature of the mass was run up above 400° F., water vapor continued to come off.

After a series of experiments, I evolved 50 the theory that the tar and light oils are in close alliance or bond and that being so in bond their combined specific gravity is so near that of water, that the tar and oils remain in suspension and do not precipitate or settle out.

55 I then conceived the idea that if it were possible to break the bond between the oils and the tar, it might be possible to secure a lower viscosity and to secure a differentiation in specific gravity, which would permit the oils to go to the top and the tar to go to the bottom and thus parting from the water.

In accordance with this theory, I slowly raised the temperature of the mixture by the use of exhaust steam and I found that

when a temperature of about 175° F. was reached, the mass began to evolve vapors of the light oils. This evolution of vapors was not rapid enough to cause agitation of the mass, but was conducted gently, so that the 70 light oil vapors come off slowly. As soon as this evolution of oil vapors began, I noticed the precipitation of tar began. I 75 gently and slowly raised the temperature further and found that the evolution of vapors suddenly stopped and, at a slightly higher temperature, evolution of further vapors began. I am not able to account for the sudden and sharp cessation of vapor pressure which occurred, but I assume that it 80 was due to the definite boiling points of the lighter oils, such as benzol, toluol, naphthol, xylol, etc.

I found that with the expenditure of 85 very little heat, I was able to drive off the light oils and precipitate a large part of the tar. The emulsion was never brought to the boiling point of the water content. The light oils were easily condensed and 90 formed a valuable by-product.

I have since conducted tests of the process 95 on a commercial scale and find that it works satisfactorily, recovering light oils and tar with the use of exhaust steam at about 3 to 5 lbs. gauge pressure.

I have, therefore, run the emulsion of 100 wash oils and tar and water into a closed well to conserve the light oils and I find that the yield of light oils is thereby considerably increased.

While the process, as at present carried out, is a batch process, I believe, from my knowledge of the operation thereof, that it can easily be made a continuous process. I have, by my discovery, disposed of an expensive nuisance about a gas plant and turned the same into a profit.

Now, in order to acquaint those skilled in the art with the manner of constructing and operating a device embodying my invention, I shall describe in connection with the accompanying drawings, a specific manner of carrying out the method.

In the drawings:

Figure 1 is a diagram of a system in which 115 my invention is embodied; and

Fig. 2 is a diagram illustrating my theory of the union of the tar and the light oils.

In Fig. 1 I have shown diagrammatically 120 the operative parts of a water gas plant. The steam boiler 1 has a steam supply main 2, which is connected through a valve 3 with the generator 4. The generator 4 is a closed chamber in which a bed of fuel 5 is maintained upon suitable grates, or the like. 125 This fuel is adapted to be brought to incandescence by means of a draft of air through the air supply pipe 6, the valve 7 being then opened. The products of combustion pass through the discharge pipe 8 130

over to the carbureter 9, the valve 10 in said pipe then being opened, and the valve 11 in pipe 12 being closed, so that the hot gases from the incandescent fuel bed 5 are driven over through the carbureter, down through the brick checker work 13 in said carbureter, through the pipe 14, and from thence through the superheater 15 and out at the stack 16, valve 17 at this time being open and valve 18 in the discharge pipe 19 being closed.

The superheater 15 is substantially filled with checker work 20 for absorbing the heat of the gases, which are then discharged to atmosphere. The carbureter has an oil supply pipe 21, including a control valve 22, to permit gas oil to be discharged into the carbureter. This oil is supplied at approximately 125 lbs. pressure during the gas forming stage, as will be described later. When the body of fuel 5 has been brought to incandescence, the air valve 7 is closed, the valve 10 of the discharge pipe 8 is closed, and valve 11 opened, and the stack 16 is cut off, valve 17 being closed, and the valve 18 in gas pipe 19, is then opened, and steam from the boiler 1, through the main 2 and valve 3 is forced down through the fuel bed 5, discharge pipe 12, through the carbureter 9, superheater 15, and over into the hydraulic main 23, where the pipe 19 dips under the level of the liquid 24 to form a water seal. From thence the gas passes up through the pipe 25 into the scrubber or cooling tower 26, where the gas is brought to substantially atmospheric temperature by means of a spray of water from the supply pipe 27. Instead of a spray condenser or cooling tower 26 a water tube condenser may be employed. The gas rises through the scrubber 26 or through the condenser and thence through pipe 28 it is discharged preferably by means of a suitable pump, into the equalizer tank 29, which is a suitable gas holder for equalizing the pressure and the supply to the gas holder between periods of operation of the generator. The equalizer 29 comprises an inverted cup having a water seal, as is well understood by those skilled in the art, and this equalizer has a discharge pipe 30 which leads to a gas holder and purifier of a kind well known in the art.

The structure thus far described is old and operates in a well known manner. The generator and carbureter, together with superheater, operate on three minute intervals in normal operation, that is, three minutes are devoted to bringing the generator to heat, and heating up the carbureter and superheater, and then for three minutes the air is shut off, valves are reversed, steam is forced down through the generator and water gas is formed and oil is, at the same time, sprayed into the carbureter to enrich the gas which is thus generated.

The gas which is driven off from the generator 4 contains a certain amount of tar and oils in volatile form and the cracking of the gas oil, which is sprayed into the carbureter 9, results in the formation of certain 70 oils and tar, which are carried in more or less vaporized form, over into the hydraulic main 23 and when the gas bubbles up through the water seal 24, the tar and light oils are cooled and condensed and picked up 75 with the liquid in said water seal. At the same time, the water in the water seal absorbs a certain amount of ammonia, sulphur compounds, and the like. The cooling of the gas is completed in the cooling tower 26 or 80 other suitable condenser. The liquid from the hydraulic main 24 and the condenser is discharged, as by way of the pipe 31, to the receiving tank or well 32 which, according to my invention, is formed as a closed tank 85 in order to avoid loss of the aromatic and other light oils which are carried by the water of the water seal over into such receiving tank. This is a departure from the prior practice which was to vent the settling 90 well to atmosphere. The condensate from the condenser 26 likewise is discharged through pipe 33 into the receiving tank 32, so that said receiving tank receives the tar, 95 light oils, and liquid discharged from the hydraulic main and from the condenser. This liquid contains the tar and light oils both in separate form and in the form of a water emulsion and, as explained heretofore, such emulsion is extremely difficult to 100 break up into its constituents. A certain part of the tar deposits in the bottom of the receiving tank and may be drawn off at the pipe 35, so that separation of such part is not necessary. However, the part which 105 will not separate by gravity is pumped out by means of a pump 36 and discharged into the separator 37, as by means of the pipe 38, where the liquid emulsion is subjected to heating by means of the steam coils 42 contained in said separator.

These heating coils 42 are connected preferably to the exhaust steam pipe 39 of the engine 40, or live steam may be admitted from the pipe 41 under the control of suitable valves. The steam coils 42 are adapted to discharge water drainage at 43, this water being preferably returned to the steam boiler 1. The emulsion is subjected to heating by waste steam at approximately 3 to 5 lbs. 120 pressure, the temperatures of steam being approximately 230° F. However, the emulsion is not heated to the boiling point of water, but is kept at a temperature slightly lower than the boiling point of water 125 by suitably controlling the supply of steam or the heating coil surface so that the water content of the emulsion will not distill or boil over. The dome of the separator is connected through pipe 44 with the condenser 45, said 130

condenser comprising, in this case, a coil of pipe cooled by a water jacket 46. Any other suitable form of condenser may be employed. In the winter season no condensing water will be necessary. The light oils are condensed in the coil 45 and discharged into the receiving tank 47. The heating of the emulsion is carried on for from 14 to 24 hours, the time being a function of the steam temperature over the area of the heating surfaces, to insure the thorough separation of light oils and tar, and at the end of this time the mixture is brought fairly close to the boiling point of water, and all of the light oils which can be extracted at that temperature are driven off. I contemplate circulating the mass in order to assist in the first separation, but in the process as heretofore carried out, I have not done so. At the end of the heating process the water liquor will have completely separated from the tar.

All of the liquid which is separated by the water seal and the condenser, and which may be termed tar and light oils and water which is discharged into the tank 32, comprises approximately 30 to 50% commercial tar and 50 to 70% of the emulsion to which I have heretofore referred. The water from the receiving tank 32 may be pumped back to the hydraulic main 23, but the emulsion is not suitable for this purpose as it tends to clog up the pipes or destroy the gas seal at 24. The emulsion is not suitable for maintaining a water seal at 23 because it tends to froth in the hydraulic main and may be drawn back into the gas take off pipe 19 and there catch fire. The emulsion is, therefore, pumped to the separator and is subjected to the treatment which I have above outlined. From my study of the problem, I am of the opinion that the gradual heating below the boiling point of the water, but above the boiling point of the light oils, tends to free the bond between the tar and the oils without appreciable agitation of the mixture. Apparently the freeing occurs in the mass of the liquid and the oil tends at once to float to the top and the tar to sink to the bottom. Whether the oil rises as a liquid or a vapor, I am not able to say. I am of the opinion that it comes to the top, partly as a vapor and partly as a liquid. The recovery of the oil may be omitted, that is, it may be discharged to the atmosphere or burned under the boiler if so desired, or otherwise disposed of. It can be seen that my process is not the usual fractioning process for taking off successive cuts from a still because first, I start with an emulsion, not a solution and, second I do not bring the mixture or emulsion to the boiling point nor does ebullition occur. Finally the separation of water and tar is actual gravity separation and not fractionation. It appears to

be necessary to vaporize off the oils to get them out of contact with the tar, otherwise they would tend to re-combine.

I have pictured in Fig. 2 diagrammatically, what according to my theory is the situation in the emulsion, namely, that a particle of tar and a particle of oil cling together, the oil particle tending to raise the mass to the top because the oil is of a specific gravity of approximately .70 to .80, whereas the tar tends to drop to the bottom, the tar being of a specific gravity of approximately 1.07 to 1.10. The water or liquor in which this emulsion is formed is somewhat heavier than pure water, as it contains salt, ammonia, sulphur, and the like, the result being that the particle which I have pictured in Fig. 2, remains in suspension in the water at normal temperatures and pressures and the oil will not separate from the tar nor will the tar precipitate. I conceive that by bringing the entire mass to a temperature which is approximately that of the boiling point of the light oils, the oil and tar are separated in the body of water with the result that the tar precipitates and the oil rises to the top and is there vaporized or re-condensed at the water level.

I conceive that this process can be hastened by reducing the atmospheric pressure upon the mass to the point of lowering the boiling point of the oil and thus causing separation. This I have not yet been able to try, but I believe it will assist. Also, it may be hastened by increasing the heating surfaces or steam temperatures of the heating coil.

Now while I have described a specific apparatus and its mode of operation to carry out my invention, I do not intend to be limited to the details which I have shown and described, except as the same appear in the appended claims.

I claim:

1. The process of precipitating tar and recovering light oils from the emulsion condensate of a gas plant which comprises heating the emulsion slowly to the boiling point of the light oils but below the boiling point of the water admixed therewith until the tar precipitates.

2. The process of precipitating tar from an emulsion of light oil, tar and water which comprises heating up the emulsion to a temperature below the boiling point of the water admixed therewith, but at approximately the boiling point of the light oil.

3. The process of separating light oils and tar from an emulsion of water which comprises heating the mass to a temperature below the boiling point of water, but to a temperature high enough to evolve vapors of the light oils, precipitating the tar at the bottom of the mass of liquid, and separately condensing the vapors of light oils.

4. The process of recovering light oils from a water emulsion of tar and oils washed out of the gases in a gas plant which consists in heating the emulsion to volatilize the light oils therein and free the tar by gravity, and withdrawing and condensing the volatilized oils.

5. The process of precipitating tar from an emulsion of water, tar and light oils, which comprises warming the emulsion to free sufficient of the oil from the tar to precipitate the tar by gravity.

6. The process of recovering tar from a water emulsion of tar and oils washed out of the gases in a gas plant which consists in warming the emulsion to free the tar and the light oils from each other and separating the tar by settling of the same out of the water.

20 7. The process of separating light oils and

tar from an emulsion of water, which consists in heating the mass of liquid fluid to a temperature slightly above the boiling point of the light oils, but below the boiling point of water, drawing off the resultant vapors of light oils, causing the tar separated from the said light oils to gravitate to the bottom of the mass of liquid fluid, condensing the light oil vapors, and withdrawing the said tar from the bottom of the remaining mass 25 of liquid.

8. The process of breaking up a water emulsion of tar and oils washed out of the gases in a gas plant which consists in maintaining the mass comparatively quiet and 30 heating to a temperature above 170° F. and below 212° F. at atmospheric pressure.

In witness whereof, I hereunto subscribe my name this 15th day of December, 1924.

WILLIAM F. DIETZSCH.
